5 Claims. (Cl. 196—50)

1 This application is a continuation-in-part of our previously filed copending application relating to a hydrocarbon conversion process, Serial No. 34,974, filed June 24, 1948, now abandoned.

This invention relates to the endothermic conversion of substantially olefin-free hydrocarbon fractions containing naphthenes and/or paraffins and boiling approximately within the gasoline range. It is more specifically concerned with a particular method of reforming straight-run gasolines and naphthas in the presence of hydrogen and a platinum-containing catalyst.

The increasing use of high compression, spark ignition, internal combustion engines, has brought about a growing demand for high octane number motor fuels. This has been accompanied by a decrease in the demand for gasolines possessing only moderate or low antiknock characteristics. As a result of this shift in demand, petroleum refiners are faced with two problems, namely, how to produce greater quantities of high octane number gasolines, and how to utilize or dispose of large amounts of low octane number fuels such as straight-run gasolines and naphthas. A single solution to both problems lies in the conversion of low grade gasolines to those of higher grade. At least one process, thermal reforming, directed toward this end, has been used commercially. However, this particular process is limited in its ability to produce high octane number products. In addition, the reformate yield is comparatively low, particularly when a fairly high octane number product is being produced. Certain catalytic reforming processes have been proposed that are capable of producing reformate of higher octane number than can be obtained by means of thermal reforming. However, the yield-octane number relationships of such processes generally are no better than that for thermal reforming. This, together with the need for frequent regenerations and the short catalyst life has largely limited the commercial utilization of these processes to certain specialized applications such as the conversion of methylcyclohexane and normal heptane to toluene.

Recently, a superior reforming catalyst has been developed, said catalyst comprising platinum and alumina. This catalyst is capable of increasing the octane number of straight-run gasolines and naphthas to values that are much higher than those that can be reached with thermal reforming and, in addition, the yield-octane number relationship is much better than are the corresponding relationships obtained in

2 either thermal reforming or in the prior catalytic reforming processes. Equally important is the fact that this catalyst is substantially non-regenerative when used under proper processing conditions, and frequently can be used for months without regeneration. Inasmuch as the characteristics of platinum-alumina reforming catalysts are different from those of other reforming catalysts, processes employing this type of catalyst should be different from processes using other types in order to make the best use thereof. We have invented a process that is particularly suitable for the most economical and efficient use of these improved platinum-alumina catalysts.

In one embodiment our invention relates to an improved conversion process providing for the use of a minimum quantity of a platinum containing catalyst, and comprises heating a substantially olefin-free hydrocarbon reactant containing saturated hydrocarbons and boiling approximately within the gasoline range to a conversion temperature, passing the heated reactant in series flow through a plurality of separate substantially adiabatic reaction zones, contacting said hydrocarbon reactant in each of the zones with a bed of said catalyst and promoting the endothermic conversion thereof, heating the hydrocarbons passing between the reaction zones to supply endothermic heat of reaction, and proportioning the catalyst among said zones to provide at least as great a quantity of catalyst in all zones successive to the first zone as is maintained in the first while simultaneously maintaining successively decreasing temperature drops in said fraction passing serially through the plurality of zones, and the last reaction zone contains a greater quantity of catalyst than the first of said plurality of zones.

In a more specific embodiment our invention relates to a process which comprises passing hydrogen and a nonolefinic hydrocarbon fraction containing naphthenes and boiling below about 425° F. through a series of at least two separate substantially adiabatic reaction zones, each containing a catalyst comprising platinum and alumina which promotes the endothermic conversion of said hydrocarbon fraction, and heating the hydrogen and hydrocarbons passing between said zones to approximately the temperature of the charge to the first zone, the catalyst being proportioned between the zones in such a manner that decreasing temperature drops are obtained in successive zones.

In a still more specific embodiment our inven-

tion relates to a process which comprises heating a substantially olefin-free hydrocarbon fraction containing naphthenes and boiling below about 425° F. to a conversion temperature within the range of from about 800° F. to about 950° F. passing the hydrocarbon fraction together with hydrogen in series flow through at least two substantially adiabatic reaction zones, containing a catalyst comprising platinum and alumina, at reforming conditions resulting in a net endothermic heat of reaction, heating the hydrogen and hydrocarbons passing between said zones, and correlating the inlet temperature to each of said zones with the amount of catalyst in each of said zones to obtain a temperature drop in the last zone that is less than $\Delta T/n$ and a temperature drop in each of the preceding zones that is greater than $\Delta T/4n$, where ΔT equals the sum of the temperature drops in each of the zones and n equals the number of zones.

The reforming of hydrocarbons is endothermic, the degree of endothermicity depending primarily upon the extent of conversion. Under these circumstances, it would appear that isothermal reactors would be an especially suitable type to employ. However, isothermal systems require elaborate and costly reactor designs to provide for heat exchange and they require heat transfer mediums such as flue gases or molten salts as well as heating means, hence we prefer to use the more economical adiabatic systems. Since the temperature drop from inlet to outlet in a single adiabatic reactor may be as much as 200° F. or more, we contemplate the use of at least two adiabatic reactors in series with reheating between the reactors. This arrangement narrows the range of reaction temperatures prevailing in any one reactor which in turn results in more uniform conversion and product quality as well as more uniform deposition of catalyst coke throughout the bed.

Some of the prior art catalytic reforming and hydroforming processes have employed two or more adiabatic reactors in series with interheating of the charge. In all of these processes it has been found necessary to regenerate the catalyst at regular and frequent intervals. In order to safely dissipate the heat liberated and protect the catalyst from damage, the volumetric rate of regeneration gases that is used normally is much greater than the volumetric rate of the process gases. Because of this situation and the resulting pressure drop problem, the more satisfactory engineering designs have involved equal distribution of the catalyst between the several reactors. Other processing means have operated in a manner providing varying depths of catalyst in successive beds and equal temperature drops through each bed, whereby apparatus arrangements are adapted to reactivate a uniform rate of catalyst decline through the successive beds. However, in the present substantially nonregenerative reforming process employing a platinum-containing catalyst, such as platinum on alumina, the design is not influenced by regeneration problems. But, on the other hand, because of the relatively high price of the catalyst, it is necessary to design the plant to minimize the catalyst cost. The lowest catalyst expense results when the catalyst requirement, i. e., inventory, is at a minimum for a given throughput or when the catalyst life, expressed as volume of charge stock processed per volume of catalyst, is the greatest. We have found that the minimum catalyst requirement and the maximum catalyst life generally are ob-

tained with unequal, rather than with equal, distribution of the catalyst between the various reactors. We have also found that so far as platinum-alumina catalyst is concerned, the catalyst distributions that result in the minimum catalyst requirements are substantially the same as those that give maximum catalyst life.

Catalyst apportionment is the principal determinant of catalyst requirement and life, however, we also find it practical to refer to temperature drops in the reactors in describing our process. One reason for this is that a reactor temperature drop is relatively easily determined experimentally and is directly related to the extent of the total endothermic reaction taking place in the reactor. The total endothermic reaction in turn is related to the amount of catalyst in the reactor. Another reason is that the exact proportioning in terms of relative catalyst volumes for minimum requirements is dependent upon the relative inlet temperatures, and is therefore less generally applicable than the proportioning of the temperature drops.

We have found that there are several requisites for obtaining low catalyst requirements. The first is that the catalyst be proportioned between the several reactors in such a manner that the temperature drop in the last reactor is less than $\Delta T/n$, where ΔT equals the sum of the temperature drops in each of the reactors and n equals the number of reactors. If the temperature drop in the final reactor is greater than the amount specified it will be so because a relatively high conversion is effected therein. The high conversion can only be brought about in this reactor by having a comparatively large amount of catalyst therein (i. e., the space velocity must be lower in this reactor than in the others to effect a high conversion when the other variables such as, inlet temperature, throughput, and pressure, are essentially the same as in the preceding reactors) thereby increasing the total catalyst requirement. The reason for this phenomenon is that the endothermicity per unit of conversion decreases with increasing conversion. Although this generally is true of most endothermic reactions, it is especially true in the reforming of straight-run gasoline or fractions thereof in the presence of platinum-alumina catalyst, which promote not only endothermic dehydrogenation reactions, but also exothermic hydrocracking reactions. The net reaction is endothermic throughout the range of conversion normally encountered, but it is less so at the higher conversion levels because the ratio of hydrocracking to aromatization increases with conversion for most charge stocks.

The minimum catalyst requirements always are realized when the temperature drop in the last reactor is less than $\Delta T/n$. But this does not mean that lowest catalyst requirements will automatically be realized if the temperature drop in the final reactor is any value less than $\Delta T/n$. For a two reactor system we have found that best results are obtained if said drop is greater than about $\Delta T/4n$, i. e., $\Delta T/8$. For a three reactor system, the minimum drop in the last reactor should be about $\Delta T/12n$ or $\Delta T/36$, and for a four reactor system, it should be about $\Delta T/24n$, or $\Delta T/96$. For larger numbers of reactors, the temperature drop in the last reactor should not be less than about 1% of the total ΔT , and not greater than the aforesaid $\Delta T/n$.

Another requisite for low catalyst requirements is that the catalyst be apportioned in such a manner that the temperature drop in each of the

reactors preceding the last is greater than $\Delta T/4n$. If it is less than this amount, the catalyst is not being used efficiently, i. e., there is too little catalyst and too small a conversion in the reactor with the low temperature drop and too much in at least one of the other reactors.

Although it is possible to effect substantial savings in catalyst requirements when using two reactors instead of one, further substantial savings are possible with three and four reactors. However, the use of more than four reactors seldom brings about a saving in catalyst proportionate to the increased outlay for equipment. Consequently, we ordinarily prefer to use either three or four reactors in our process. The data listed in the following table provide a comparison of the minimum catalyst requirements for several adiabatic reactor systems with the catalyst requirement for a single isothermal reactor operating at a temperature of 850° F. which is also the inlet temperature that was assumed for each of the adiabatic reactors. The other operating conditions were such as to give a conversion sufficient to raise the F-2 (motor method) octane number of a 40 octane number straight-run gasoline to 75 when using a catalyst comprising platinum and alumina.

TABLE I

No. of Adiabatic Reactors	Minimum Catalyst Requirement
1	76.0
2	3.5
3	1.9
4	1.5
Infinite ¹	1.0

¹ Equivalent to an isothermal reactor.

The data show the great decrease in catalyst requirement obtained in going from a one reactor system to a two reactor system with interheating. They also show that a considerable further benefit is obtained by going to a three or a four reactor system, but that thereafter the savings are of less consequence.

The catalyst distributions corresponding to the minimum catalyst requirements listed in Table I are shown below:

TABLE II

Reactor No.	1	2	3	4
Catalyst Distribution, Percent:				
One Reactor System	100			
Two Reactor System	34	66		
Three Reactor System	25	28	49	
Four Reactor System	13	19	25	43

It will be observed that in all cases, the minimum catalyst requirement was realized with unequal amounts of catalyst in the various reactors. It should also be observed that the minimum catalyst requirement always is found in some combination of successively decreasing temperature drops in multiple adiabatic reactor systems employing interheating. This is one of the reasons that the temperature drop in the last reactor should not exceed $\Delta T/n$.

The hydrocarbon stocks that may be converted in accordance with our process comprise non-olefinic hydrocarbon fractions containing saturated hydrocarbons, particularly naphthenes. By the term nonolefinic we mean substantially olefin-free, i. e., a few per cent of olefins can be present in the charge in some types of operation.

Suitable stocks include narrow boiling fractions rich in naphthenes as well as substantially pure naphthenes such as cyclohexane and methylcyclohexane. The preferred stocks are those consisting essentially of naphthenes and paraffins, although relatively minor amounts of aromatics also may be present. The naphthenes are dehydrogenated to aromatics and the paraffins are hydrocracked to lower boiling paraffins. This preferred class includes straight-run gasolines, natural gasolines, and the like. The gasoline may be a full boiling range gasoline having an initial boiling point within the range of from about 50° to about 100° F. and an end boiling point within the range of about 325° to about 425° F., or it may be a selective fraction thereof which usually will be a higher boiling fraction commonly referred to as naphtha, and generally having an initial boiling point of from about 125° to about 250° F., and an end boiling point within the range of about 350° to about 425° F. The expression "straight-run gasoline fraction" as used herein is intended to include both naphthas and full boiling gasolines.

The platinum-alumina catalysts that are preferred for use in our process may contain substantial amounts of platinum, but, for economic as well as for product yield and quality reasons, the platinum content usually will be within the range of from about 0.05% to about 5.0%. A particularly effective catalyst of this type contains relatively minor amounts, usually less than about 3% on a dry alumina basis, of a halogen, especially chlorine and fluorine. One method of preparing these catalysts comprises adding a suitable alkaline reagent such as ammonium hydroxide or carbonate to a salt of aluminum, such as aluminum chloride, aluminum sulfate, aluminum nitrate, and the like, in an amount sufficient to form aluminum hydroxides, which upon drying, can be converted to alumina. The halogen may be added to the resultant slurry in the form of an acid such as hydrogen fluoride or hydrogen chloride, or as a volatile salt such as ammonium fluoride or ammonium chloride. A colloidal suspension of platinic sulfide is then prepared by introducing hydrogen sulfide into an aqueous solution of chloro-platinic acid until said solution reaches a constant color, which is usually a dark brown. The resultant colloidal suspension of platinic sulfide is commingled with the aluminum hydroxide slurry at room temperature followed by stirring to obtain intimate mixing. The resulting materials are then dried at a temperature from about 200° to about 400° F. for a period of from about 4 to about 24 hours or more to form a cake. The resulting material may then be converted into pills or other shaped particles. Thereafter the catalyst may be subjected to a high temperature calcination or reduction treatment prior to use.

Reforming operations carried out in accordance with our process in the process of platinum-alumina catalysts ordinarily will be carried out employing inlet temperatures of from about 800° F. to about 950° F. At inlet temperatures much below about 800° the reaction rates are quite slow and very low space velocities must be employed to obtain appreciable conversions. At inlet temperatures much in excess of 950° F. an appreciable amount of thermal reaction takes place in the initial part of the catalyst bed accompanied by a poorer liquid recovery and more rapid catalyst deactivation.

The pressure at which our process is conducted

usually will be within the range of from about 50 to about 1200 pounds per square inch; a weight hourly space velocity, which is defined as the weight of hydrocarbon charge per hour per weight of catalyst in the reaction zones, within the range of from about 0.2 to about 40; and the amount of hydrogen charged along with the hydrocarbons usually will be from about 0.5 to about 15 mols. per mol. of hydrocarbon. When our process is operated at carefully correlated conditions within the ranges outlined above, it is substantially nonregenerative and can be operated for weeks and even months without the necessity of regenerating the catalyst by burning the carbon therefrom.

Other platinum-containing catalysts that may be used in our process include platinum on charcoal, platinum on asbestos, and platinum on bases that possess cracking activity such as silica-alumina composites. The corresponding palladium catalysts frequently can be used in our process.

Sulfur compounds appear to be at least temporary poisons for platinum-alumina catalysts, consequently, the charging stock should be substantially free from these materials when a catalyst of this type is employed.

The features of the recent invention will be apparent from the following description of the attached drawing which illustrates a particular method of conducting a reforming operation in accordance with our process.

Referring now to the drawing, a low sulfur, full-boiling range straight-run gasoline which contains naphthenes and paraffins is charged through line 1 containing valve 2 and is picked up by pump 3 and passed through line 4 containing valve 5 into fractionator 6. A light naphtha with an end point of about 150° F. is taken overhead from fractionator 6 through line 1, condenser 8, line 9, and is passed into receiver 10. The condensed naphtha in receiver 10 is passed into line 11, pump 12 and line 13. A portion of the light naphtha passing through line 13 is diverted through line 14 containing valve 15 and directed into the top of fractionator 6 as reflux.

Heavy naphtha is withdrawn from fractionator 6 through line 16 containing valve 17 and is joined by a hydrogen recycle stream passing through line 18. The commingled streams flow through heater 19 and into reactor 20. The molal ratio of hydrogen to hydrocarbon in the charge to reactor 20 is 6:1. The combined stream of hydrogen and hydrocarbon flows in series through reactor 20, line 21, heater 22, line 23, reactor 24, line 25, heater 26, line 27 and reactor 28. The catalyst comprises a composite of platinum, alumina, and fluorine, containing 0.1% platinum and 0.7% fluorine. The total amount of catalyst in the three reactors is proportioned so that 25% of it is in reactor 20, 25% of it is in reactor 24, and 50% is in reactor 28. The inlet temperature to reactors 20, 24, and 28, is 850° F. The outlet temperatures for the same three reactors are approximately 751, 799, and 830° F. The weight hourly space velocity is 2 and the total pressure is 600 p. s. i. If desired, the reaction zones and heaters may be incorporated in a single vessel; separate vessels are not a necessity.

The effluent from reactor 28 is withdrawn through line 29 and condenser 30 and is passed through line 31 into receiver 32. In this receiver hydrogen and gaseous hydrocarbons are separated from liquid hydrocarbons. Excess gas is vented through line 33 containing valve 34 and,

10
5

if desired, may be charged to deethanizer 48. The remainder is recycled to the reactor section of the plant. If it contains appreciable amounts of hydrogen sulfide it is passed through line 35 containing valve 36 and into hydrogen sulfide separator 37. Said separator may comprise a caustic wash system, a diethylaniline-ethylene glycol system, or any other system that will effectively remove hydrogen sulfide. The effluent therefrom is passed through line 38 containing valve 39 and into compressor 40 from which it is sent through line 48 to reactor 20. If the recycle hydrogen stream is low in hydrogen sulfide the H₂S separator may be bypassed via line 41 containing valve 42.

The liquid hydrocarbon in receiver 32 are withdrawn through line 43 containing valve 44, are picked up by pump 45, and are sent through line 46 containing valve 47 into deethanizer 48. Absorption oil, prepared as hereinafter described enters the deethanizer near the top. Ethane and lighter gases are removed from the vessel through line 49 containing valve 50. The deethanized liquid bottoms product is withdrawn from deethanizer 48 through line 49a containing valve 50a, is joined by the light straight-run naphtha from fractionator 6 passing through line 43 containing valve 51, and the combined stream is charged to stabilizer 52.

The fractionating conditions in stabilizer 52 are regulated to obtain a bottoms product of the desired vapor pressure which usually will be about 10 pounds. Light hydrocarbon such as propane together with some butanes are taken overhead from stabilizer 52 through line 53, condenser 54, and are passed through line 55 into receiver 56. The condensed hydrocarbons in receiver 56 are withdrawn through line 58 and a portion thereof is passed through line 59 containing valve 60, through pump 61 and by means of line 62 containing valve 63 is sent to the top of stabilizer 52 where it serves as reflux. The excess light hydrocarbons are withdrawn through line 58 containing valve 57 and are sent to storage or are otherwise disposed of.

The stabilized hydrocarbons are withdrawn from vessel 52 through line 64 containing valve 65 and are sent to storage. This stream constitutes a major product of the process. A portion of the stream flowing through line 64, is passed through line 66 containing valve 67 and is directed into stripper 68. The vapor pressure of this stream is reduced in order to make a suitable absorption oil from it by removing light hydrocarbons overhead as vapors through line 69 containing valve 70 and passing them into stabilizer 52. The stabilized hydrocarbons, which may have a vapor pressure of 1 or 2 pounds, are then withdrawn from the bottom of stabilizer 68 and are passed through line 71 containing valve 72, pump 73 and valve 74 to the top of deethanizer 48.

If a higher boiling naphtha is to be charged to our process, prefractionator 6 and the auxiliary equipment used in conjunction therewith may be eliminated. The reactors should not be made of iron unless they contain a suitable liner, because iron has a deleterious effect upon the platinum-alumina catalyst. The catalyst need not necessarily be disposed as fixed beds in the reactors in all types of operations; it can, for example, be present in a finely divided form and the hydrogen and hydrocarbons passed upwardly therethrough in a "fluidized-fixed bed" type of operation.

An alternative method of operation comprises

passing a portion of the recycle hydrogen stream, which contains an appreciable quantity of low boiling hydrocarbons, to absorber 48 and therein using a portion of the bottoms of fractionator 6 as a lean absorber oil. The rich absorption oil is returned to fractionator 6. The liquid hydrocarbons in receiver 32 are then passed, together with the light naphtha from fractionator 6, to stabilizer 52. In this embodiment stripper 68 may be eliminated. The overhead product from stabilizer 52 may or may not be returned to the absorber as desired.

From the foregoing specification it can be seen that we have provided an improved substantially non-regenerative method for the reforming of hydrocarbons, particularly in the presence of platinum-alumina catalysts. Further, we are not concerned with providing a "switch" or regenerating operation and by means of our process the most efficient use and the favorable characteristics of this type of catalyst are utilized to the fullest extent, with the result that higher yields of higher octane number products are produced with a smaller amount of catalyst and at a longer like than would be possible with conventional methods of operation.

We claim as our invention:

1. In an endothermic, substantially non-regenerative catalytic process for the reforming of a substantially olefin-free, normally liquid gasoline fraction in contact with a platinum-containing catalyst, the improved method of operation providing for the economical utilization and minimum quantity of the platinum-containing catalyst, which comprises passing the gasoline fraction through a series of at least two reaction zones containing separate beds of said catalyst, proportioning the catalyst among said zones so that each zone of the series succeeding the first zone contains a quantity of catalyst at least equal to that in the first zone of the series and the last zone of the series contains a greater quantity of catalyst than each preceding zone, heating the gasoline fraction to reforming temperature prior to its introduction to each of said zones, and correlating the inlet temperature of the heated gasoline fraction to each zone with the amount of catalyst therein to obtain a temperature drop in said last zone that is less than $\Delta T/n$ and a temperature drop in each preceding zone of the series that is greater than $\Delta T/4n$, where ΔT equals the sum of the temperature drops in said zones and n equals the number of zones in the series.

2. In an endothermic, substantially non-regenerative catalytic process for the reforming of a substantially olefin-free, normally liquid gasoline fraction in contact with a platinum-containing catalyst, the improved method of operation providing for the economical utilization and minimum quantity of the platinum-containing catalyst, which comprises passing the gasoline fraction through a series of at least three reaction zones containing separate beds of said catalyst, proportioning the catalyst among said zones so that each zone of the series intermediate the first and the last contains a quantity of catalyst at least equal to that in the first zone and the last zone of the series contains a greater quantity of catalyst than each preceding zone, heating the gasoline fraction to reforming temperature prior to its introduction to said first zone and reheating it to reforming temperature between successive zones of the series, and correlating the inlet temperature of the heated gaso-

line fraction to each zone with the amount of catalyst therein to obtain a temperature drop in said last zone that is less than $\Delta T/n$ and a temperature drop in each preceding zone of the series that is greater than $\Delta T/4n$, where ΔT equals the sum of the temperature drops in said zones and n equals the number of zones in the series.

3. In an endothermic, substantially non-regenerative catalytic process for the reforming of a substantially olefin-free, normally liquid gasoline fraction in contact with a platinum-containing catalyst, the improved method of operation providing for the economical utilization and minimum quantity of the platinum-containing catalyst, which comprises passing the gasoline fraction through a series of three reaction zones containing separate beds of said catalyst, proportioning the catalyst among said zones so that the second zone of the series contains a quantity of catalyst at least equal to that in the first zone of the series and the third zone of the series contains a greater quantity of catalyst than said second zone, heating the gasoline fraction to reforming temperature prior to its introduction to said first zone and reheating it to reforming temperature between the first and second zones and between the second and third zones, and correlating the inlet temperature of the heated gasoline fraction to each zone with the amount of catalyst therein to obtain a temperature drop in said third zone that is less than $\Delta T/3$ and a temperature drop in each of said first and second zones that is greater than $\Delta T/12$, where ΔT equals the sum of the temperature drops in said zones.

4. In an endothermic, substantially non-regenerative catalytic process for the reforming of a substantially olefin-free, normally liquid gasoline fraction in contact with a platinum-containing catalyst, the improved method of operation providing for the economical utilization and minimum quantity of the platinum-containing catalyst, which comprises passing the gasoline fraction through a series of three reaction zones containing separate beds of said catalyst, proportioning the catalyst among said zones so that the first and second zones of the series contain approximately equal quantities of catalyst and the third zone of the series contains a greater quantity of catalyst than each of said first and second zones, heating the gasoline fraction to reforming temperature prior to its introduction to each of said zones, and correlating the inlet temperature of the heated gasoline fraction to each zone with the amount of catalyst therein to obtain a temperature drop in said third zone that is less than $\Delta T/3$ and a temperature drop in each of said first and second zones that is greater than $\Delta T/12$, where ΔT equals the sum of the temperature drops in said zones.

5. The method of claim 1 further characterized in that said reaction zones are maintained under substantially adiabatic conditions.
